UNITED STATES PATENT OFFICE

EWALD ALVERMANN, OF DUSSELDORF, GERMANY

PRODUCTION OF SEAMLESS TUBES

Application filed March 30, 1927, Serial No. 179,612, and in Germany November 1, 1926.

My invention refers to the production of seamless metal tubes. It has for its primary object to provide means whereby such tubes can be produced in a more perfect and less expensive manner than was hitherto possible.

In the production of tubes from steel or wrought iron, more particularly in recent times, the various methods of producing 10 seamless tubes have come more and more to the fore. The efforts made on the world markets to replace welded tubes by seamless tubes have however up to the present been only partially successful, inasmuch as 15 hitherto no one has succeeded in perfecting methods of production for more than certain sizes of seamless tubes. By far the larger proportion of the tubes made of wrought iron, that is, about 75 per cent of 20 the world consumption, are produced welded, and the only reason for the present day preference for welded tubes is that the production of seamless tubes is more expensive. This is due to the high cost of the raw material and to the unsatisfactory methods of 25 manufacture. This is more particularly the case with the larger sizes of tubes, which in Germany are produced almost exclusively on the pilgering mill by Perrins' process. 30 By this process a seamless hollow block is rolled out hot into a seamless tube in steps. This operation of rolling is known, and it may be divided into two simultaneous operations, in the first of which a part of 35 the thick wall of the hollow or tubular body is reduced in thickness or reduced by forging, and in the second of which this tube reduced by forging is smoothed in the second part of the roll calibre and reduced for 40 uniformity of dimensions. It is this second part of the rolling operation which requires tools that work with precision but that wear rapidly, and also machines on which the demands are severe and which involve a 45 high consumption of power. The final product of these two simultaneous operations is one which is secured only by the operators exercising the greatest care. The pilgering method has the further disadvantage that 50 during the rolling operation the forward

end of the blank is rolled out at higher temperatures than is its rearward end, the result of which is that the final product is not uniform in quality. Notwithstanding that these pilgering mills are provided with 55 the best auxiliary devices and are of exact construction, their output is yet very small and insufficient to enable a seamless tube to be produced which is as cheap as the welded tube.

The purpose of the present invention is to remove the disadvantages hereinbefore described of the known method, or at least to diminish them very considerably.

According to the present invention the 65 rolling operation that is necessary to produce a seamless tube from a pierced bloom, billet or the like is divided and carried out by two separate rolling mills, that is to say, the first rolling mill does the preliminary 70 work of forging the bloom, billet or the like to produce a roughly forged intermediate blank of considerably greater wall thickness and smaller length than the tube to be produced, while the second rolling mill is 75 provided to convert this blank into the finished tube of predetermined greater length and smaller wall thickness, without, however, reducing the outer diameter.

The first operation is carried out in a 80 pilgering mill, the second operation, in a double groove (two high) rolling mill (plug mill). After the completion of the pilgering the blank is cut up into a number of pieces or sections and these sections, after being 85 reheated, are converted into tubes in the double groove (two high) rolling mill by being rolled over a stationary mandrel.

The process according to the present invention and a plant for carrying it out are 90 illustrated diagrammatically in the accompanying drawings, in which

Fig. 1 is a diagrammatic plan of the plant, and

Fig. 2 a diagram illustrating the hollow or tubular body and the product of the process in stages.

In the drawings, *a* is a pilgering mill as used in rolling blooms, billets and the like according to Perrins' process; *b* a finishing 100

rolling mill, *c* a furnace, *d* a hot-iron saw. The hollow bloom 1 illustrated in the drawing is rolled out in the pilgering mill to produce a thick-walled roughly forged intermediate blank 2; the latter is then cut up into sections by the hot-iron saw *d*, and these sections, after passing through the furnace *c* are rolled out upon the double groove (two high) rolling mill *b* one after the other, by one or 10 more operations over a mandrel to produce the finished tube 3. The pilgering mill *a* produces roughly forged thick-walled intermediate blanks in fairly large quantities, because the double groove (two high) rolling 15 mill *b* is in a position to take over the main part of the rolling work in finishing the hollow blanks 2 that have been cut up by the hot-iron saw *d* and heated in the furnace *c*, and is also able to convert these roughly 20 forged sections into tubes having thin walls in one or more operations.

By the combination of a pilgering mill and a double groove (two high) rolling mill a method of producing tubes is provided which 25 does away with the disadvantages of the known rolling method described and embodies the advantages of the latter. Inasmuch as there is also an output which is several times as great as that of a pilgering mill, 30 the cost of production of seamless tubes is, according to the invention, considerably reduced and there is thus the possibility presented of the seamless products entering into better competition with welded tubes.

35 I wish it to be understood that I do not desire to be limited to the exact details of construction shown and described for obvious modifications will occur to a person skilled in the art.

40 In the appended claims the term "bloom" is intended to include billets and the like.

I claim:—

45 1. The method of producing seamless tubes comprising reducing the wall thickness of a hollow bloom by rolling according to the pilgering process to produce a roughly forged intermediate blank of materially greater wall thickness throughout and materially less length than the finished tubes, cutting said 50 blank in two, reheating the roughly forged cut pieces and subjecting said pieces to a different rolling process to convert them into tubes of predetermined greater length and smaller wall thickness than, but having sub- 55 stantially the same outer diameter as said roughly forged pieces.

2. The method of producing seamless tubes comprising reducing the wall thickness of a hollow bloom by rolling according to the 60 pilgering process to produce a roughly forged intermediate blank of materially greater wall thickness throughout and materially less length than the finished tubes, cutting said blank in two, reheating the roughly forged 65 cut pieces and subjecting said pieces to a dif-

ferent rolling process over a mandrel to convert same into tubes of predetermined greater length and smaller wall thickness than, but having substantially the same outer diameter as said roughly forged pieces.

3. The method of producing seamless tubes comprising reducing the wall thickness of a hollow bloom by rolling on a pilgering mill to produce a roughly forged intermediate blank of materially greater wall thickness throughout and materially less length than the finished tubes, cutting said blank in two, reheating the roughly forged cut pieces and subjecting said pieces to a further rolling operation over a mandrel in a double groove (two-high) mill to convert same into tubes of predetermined greater length and smaller wall thickness than, but having substantially the same outer diameter as said roughly forged pieces.

70 75 80 85 In testimony whereof I affix my signature.
EWALD ALVERMANN.
